UNITED STATES PATENT OFFICE.

HERMAN H. WERGES, OF EAST ALTON, ILLINOIS.

PACKAGE-TIE.

1,279,191.

Specification of Letters Patent. Patented Sept. 17, 1918.

Application filed September 13, 1917. Serial No. 191,175.

To all whom it may concern:

Be it known that I, HERMAN H. WERGES, a citizen of the United States, residing at

East Alton, in the county of Madison and

5 State of Illinois, have invented certain new and useful Improvements in Package-Ties; and I do hereby declare the following to be a full, clear, and exact description of the invention, such as will enable others skilled 10 in the art to which it appertains to make and use the same.

This invention relates to a new and useful package tie and has for its object among others, to provide a simple, cheap and inexpensive one, which is of durable and substantial design, and which can be quickly and readily manipulated to effectively secure and bind a package or packages into a neat and compact bundle.

20 With these and other objects in view the invention comprises the various novel features of construction, combination and arrangement of parts as will be more fully described hereinafter and specifically claimed.

25 Referring to the drawings,

Figure 1 represents a perspective view of my novel construction of package tie operatively attached to a package or bundle.

30 Fig. 2 represents a plan view of the package tie showing the manner of attaching the cord or other flexible element thereto.

Fig. 3 represents a plan view of the package tie with the flexible element wound 35 around one end thereof, and

Fig. 4 represents a longitudinal sectional view taken on the line 4—4 of Fig. 2.

Similar characters of reference are used 40 to denote corresponding parts throughout the accompanying drawings and the following description.

In order that the construction and operation 45 of the invention may be readily comprehended, I have illustrated an approved embodiment thereof in the accompanying drawings and will now proceed to fully describe the same, in connection with said drawings, in which the reference numeral 1 indicates an elongated base plate, the opposite side edges 50 of which converge toward each other and terminate at one end in a rounded portion 2 and at the other end in a rounded portion 3. The opposite converging side edges of the base plate are provided with notches 4

disposed opposite to one another and at a 55 point adjacent the smaller end of the base plate.

The smaller end of the base plate, is provided with an eyelet 5, which has one of its circumferential flanges 6 countersunk with 60 in the bottom face of the base plate so that the latter may rest flat upon the package to be tied. A flexible element such as a cord or the like 7 has one end extended through the eyelet 5 and is rigidly secured to the small 65 end of the base plate by tying the end of the flexible element thereto.

The opposite or larger end of the base plate is provided with a countersunk aperture 8. A disk 9 is provided centrally with 70 an apertured boss 10 arranged to rest on the base plate in axial alinement with the countersunk aperture 8 and serves to space the disk from the base plate a sufficient distance to enable the flexible element to be wound 75 around the boss and frictionally wedged or held between the disk and the base plate in juxtaposed coils in an effective manner against casual disconnection.

The outer side of the boss 10 is provided 80 with a countersink 11 disposed in axial alinement with the boss aperture. Disposed through the apertured boss and the countersunk aperture of the base plate is an attaching eyelet 12, one of the circumferential 85 flanges of which rests in the countersink of the aperture 8 while the other circumferential flange rests within the countersink 11, said eyelet serving to securely attach the disk to the base plate. By disposing the 90 lower circumferential flange of the eyelet within the countersink of the aperture 8, the base plate may rest flat upon any package to which the tie is to be applied.

In order to facilitate easy winding of the 95 flexible element around the boss 10 between the disk and the base plate, the circumferential edge of the disk is bent and curved laterally away from the base plate as indicated by the numeral 13.

To attach the package tie, the base plate 100 is placed upon the package and the smaller end held beneath the thumb so that the free end of the flexible element may be extended longitudinally around the package, given a quarter of a turn around beneath the disk, then extended transversely around the package and wound around beneath the disk

until the end of the flexible element is taken up, thus effectively securing or tying the package into a compact bundle.

When the package tie is not in use the flexible element is wound transversely around the base plate through the notches 4 so that all liability of the flexible element becoming entangled will be eliminated and at the same time allow of the package tie 10 to be packed into the smallest possible space for keeping or for shipment. It will be noted that the notches 4 are of such depth that when the flexible element is wound around the base plate through them that the 15 outermost coil of the element will be disposed within the converging lines of the side edges of the base plate, thus leaving no projecting edges.

I claim:

20 A cord fastener for a package tie comprising in combination with the base plate having a countersunk aperture, a disk hav-

ing a central apertured boss resting on said base plate in axial alignment with said countersunk aperture thereof, said boss having a countersink in its outer side, the circumferential edge of said disk being curved laterally from said base plate, and an eyelet disposed through said apertured boss and countersunk aperture of the base plate and 25 provided at opposite ends with circumferential flanges resting in said boss countersink and the countersunk aperture of the base plate, the bottom of the eyelet resting in the same plane with the bottom of the base plate 30 to present a smooth under surface.

In testimony whereof I have signed my name to this specification in the presence of two subscribing witnesses.

HERMAN H. WERGES.

Witnesses:

W. G. MERIWETHER,
LAURA COOPER.
